UNITED STATES PATENT OFFICE

106,049

DESIGN FOR AN AUTOMOBILE ROOF AERIAL LEAD-IN

Roman Kopanski, Cleveland, Ohio, assignor to
The Ward Products Corporation, Cleveland,
Ohio, a corporation of Ohio

Application July 17, 1937, Serial No. 70,515

Term of patent 7 years

To all whom it may concern:

Be it known that I, Roman Kopanski, a citizen of the United States and a resident of Cleveland, in the county of Cuyahoga and State of Ohio, have invented a new, original, and ornamental Design for an Automobile Roof Aerial Lead-In, of which the following is a specification, reference being had to the accompanying drawing forming a part thereof, in which

Fig. 1 is a side elevation of an automobile roof aerial lead-in embodying my new design, and
Fig. 2 is a plan view thereof.

I claim:
The ornamental design for an automobile roof aerial lead-in, as shown.

ROMAN KOPANSKI.
